UNITED STATES PATENT OFFICE

TOM W. BESLEY, OF COUNCIL BLUFFS, IOWA

KITE

Application filed September 25, 1929. Serial No. 394,996.

This invention relates to improvements in kites, and more particularly to knockdown kites which may be placed upon the market dismantled in a very compact container for later assembly by the purchaser, the kite being preferably of a shape which is to some extent an imitation of an aeroplane, although the invention may have many and various uses as will be apparent to one skilled in the art.

10 In the past, many and various types of kites have been developed, and some of these were knockdown kites initially delivered to the customer in compact form to be assembled by the customer, but these kites for various reasons have in most instances proven objectionable. One major objection to these formerly known kites lies in the fact that they are of undesirably complicated construction and difficult to assemble, the complicated construction resulting in an objectionably high manufacturing cost and purchase price, and the difficult assembling operations necessary frequently result in injury to portions of the kite which frequently amount to an injury sufficient to interfere with the proper flying of the kite or disable it entirely. In every instance of which I am aware in previously known knockdown kites, the kites were not capable of absolute dismantling, but when in collapsed or knockdown form, still had many pieces hingedly connected, which pieces were merely folded into juxtaposed relative position. To assemble a kite of this character, in at least that portion of the frame which is hingedly connected, it is simply necessary to hold one stick and pull upon another stick so that practically the entire frame work will immediately be expanded into operative position. Such kites are objectionable, since, in nearly every instance, the kite will be assembled by a child, and these kites would be totally lacking in benefit to the child from an educative standpoint of view.

45 The present invention has been designed to overcome the above noted, as well as many other objections, in the provision of a kite which may be very easily and readily taken apart or assembled with minimum danger of injury unless the party assembling the kite is

extremely careless in the necessary operations.

The invention also seeks the provision of a kite which may be dismantled, which includes a minimum of actual fastening means, and in which certain portions of the kite itself cooperate with other portions to maintain parts of the structure in assembled position without the aid of extraneous means.

A further object of this invention is to provide a kite which is completely collapsible to the last piece, and yet which may be very expeditiously assembled even by a child.

Still a further object of this invention is the provision of a kite capable of being dismantled so as to occupy an extremely small space, the kite including substantially standard and readily replaceable parts.

It is still a further object of the present invention to provide a kite which, although very simple in construction, is formed to present relatively large wind surfaces in such a manner that the kite will very easily elevate itself and remain in a condition of great stability while flying.

While some of the more salient features, characteristics, and advantages of a device embodying this invention have been above pointed out, others will become apparent from the following disclosure.

The invention includes these and other features of construction and combinations of parts hereinafter described, and shown in a preferred form in the drawings, as more particularly indicated by the claims.

On the drawings:

Figure 1 is a side elevational view of a kite embodying principles of the present invention, showing the same in flying position.

Figure 2 is a bottom plan view of the kite shown in Figure 1.

Figure 3 is an enlarged fragmentary sectional view, with parts in elevation, taken substantially as indicated by the line III—III of Figure 2.

Figure 4 is an enlarged fragmentary sectional view, taken substantially as indicated by the line IV—IV of Figure 2.

Figure 5 is an enlarged fragmentary sec-

tional view taken substantially as indicated by the line V—V of Figure 2.

Figure 6 is a diagrammatic view indicating how the sheet structure embodied in the kite may be formed.

Figure 7 is a view showing various portions of the kite, exclusive of the sheet structure, in collective order.

Figure 8 is a perspective view illustrating 10 the manner in which the kite may be dismantled and packed for shipment.

Figure 9 is a front elevational view of the kite assembled.

Figure 10 is an enlarged fragmentary sectional view taken substantially as indicated 15 by the line X—X of Figure 9.

As shown on the drawings:

At the outset, it is to be understood that hereinafter and in the claims hereto annexed, 20 where the term "sticks" is used, the structure designated thereby is not to be limited to wooden elements, but is to be construed as elements of equivalent character and function made of any desirable material; and 25 where the term "sheet" is used, this term is also to be construed as meaning a structure of equivalent character and function made of any desirable material.

In the structure selected to illustrate an 30 embodiment of the present invention, there is shown a kite including a wing or plane generally indicated by the reference numeral 11, a pair of spaced body sticks 12 removably attached at their forward portion to the wing 35 11, and a cruciform rudder generally indicated by the numeral 13 mounted on the rear portions of the body sticks 12. If so desired, any suitable form of tail 14, as indicated by the dotted lines in Figure 1, may be attached 40 to the rear portion of the rudder, such a tail being some times desirable if the kite is flown in a stiff wind.

In this instance, the wing or plane 11 comprises a flexible sheet 15, preferably of paper, 45 provided with tubular margins 16, preferably formed by doubling the margin of the sheet back upon itself and securing the rim thereof to the body of the sheet by any suitable adhesive. Passing through each of the tubular margins 16 is a wing stick 17, preferably of a material at least partially resilient, and provided with conical or relatively sharpened tips 18. To form a complete wing frame sufficient to maintain the sheet 15 in 50 properly expanded or stretched position, an angular end member 19 is provided adjacent each short side of the wing. The end members 19 each have inwardly turned tips 20, the end members being apertured adjacent 55 the tips to fit over the conical tips 18 of the wing sticks, and the tips 20 being suitably apertured in the inwardly turned portions thereof for the reception of the hooked ends of a pair of dihedral or tension rods 21. 60 These tension rods 21 extend substantially

parallel to the wing sticks 17, but are relatively shorter than the wing sticks so that the latter will bow downwardly when the tension members are applied, whereby the wing will be provided with a suitable dihedral which adds greatly to the stability of the kite 70 when flying.

The body portion of the kite, in this instance, embodies a pair of spaced body sticks 12, also preferably of a material at least partially resilient. These body sticks are provided with suitable apertures 22 therethrough in spaced relationship (Figure 7) which, when the body sticks are disposed transversely to the wing 11, in alignment with spaced apertures 23 in the wing sticks 17. Adjacent these aligned apertures the tubular margins 16 of the sheet 15 are also apertured both above and below the wing sticks 17 as indicated more clearly at 24 in Figure 3. Through the aligned apertures cotter pins 25 are passed to secure the body sticks to the kite wing 11. Any desired number of cotter pins or equivalent securing means may be utilized for this purpose, but as shown in the drawings, four pins have been found to be sufficient. Between the apertures 22 in the body sticks 11 another aperture 26 is provided in each stick for the reception of a cotter pin 27 which passes through the body sticks and sheet 15 and to the eye of which an end of a small cord 28 is secured. The small cord 28 will hang in the form of a V at the apex of which the main cord 29 is attached, this latter cord being the one by which the kite is controlled during flight.

At the rear portion of the body sticks 12, the cruciform rudder 13 is provided by means now to be described. A pair of relatively short sticks 30 having semi-circularly notched ends, as indicated at 31 in Figure 4, extend transversely between the rear portions of the body sticks 12, the notched ends 31 embracing a portion of the body sticks. These transverse rods 30 increase the space between the body sticks and cause the latter, due to their inherent resiliency, to assume a pleasing curvature as indicated at 32 in Figure 2. The resiliency of the body sticks 12 effectively maintain the transverse sticks 30 in proper position without the aid of any securing means or adhesive. Between the transverse sticks 30 a sheet 33 similar to the sheet 15 and having tubular margins 34 similar to the margins 16 is connected to the body sticks, the rear portions of these sticks passing through the tubular margins, and prevents additional spreading of the body sticks while at the same time maintaining the transverse sticks 30 the proper distance apart. As seen more clearly in Figures 5 and 9, the transverse sticks 30 are each provided with a central aperture through which an upright stick 35 passes, each upright extending substan- 125

tially an equal distance above and below its corresponding transverse stick 30. Above the sheet 33 and substantially normal thereto a sheet 36 having tubular margins 37 is disposed, the margins 37 passing over the upright sticks 35. A similar sheet is provided on the sticks 35 below the sheet 33. It will be apparent from the foregoing that the transverse sticks 30 are prevented from moving away from the edges of the sheet 33 by means of the two sheets 36, and that therefore a construction equivalent to a combination of horizontal and vertical rudders, in other words a cruciform rudder, is provided which is maintained in position entirely by the sheets forming the wind surfaces for the rudder and by the resiliency of the body sticks 32.

It is to be noted that the various sheets 15, 20 33, and the two sheets 36, may be all cut from the same initial strip of material provided with tubular margins, as indicated clearly in Figure 6. Moreover, the other portions of the kite may be embodied in standard parts 25 of standard lengths, as clearly shown in Figure 7, which illustrates all of the parts necessary to form the kite in collective order, exclusive of the sheets and cotter pins.

As indicated in Figure 8, the entire kite 20 may be dismantled and packed in a compact cylinder 38, whereby the kite may be easily and readily shipped or carried from place to place.

In operation, the present invention is extremely simple. Assuming now that the kite 35 is packed in the cylinder 38 and it is desired to assemble the same, it is simply necessary to unpack the various parts and firstly spread out the sheets 15, 33, and 36. The wing sticks 40 17 are inserted one in each of the margins 16 of the sheet 15 and the end member 19 are then placed upon the protruding extremities 18 of the wing sticks. The flexible tips 20 of the end member 19 are bent inwardly, if 45 this has not previously been done by the manufacturer or shipper, and the dihedral or tension rods 21 are next hooked into the apertures in the inwardly bent strips 20. The wing is preferably disposed edgewise 50 upon the floor and pressure exerted upon the upper edge thereof sufficient to bow the wing sticks to an extent permitting the easy attachment of the dihedral or tension rods which will then maintain the wing sticks in 55 bowed positions to provide the desired arcuate wing.

After the wing is so formed, the body sticks 12 are next attached thereto by the simple expedient of inserting cotter pins 25 through the aligned holes in the body and wing sticks. Cotter pins 27 may also be inserted and the transverse cord 28 and flying cord 29 attached thereto. It is to be noted that the cotter pins 27 are spaced some distance from the forward edge of the wing,

whereby the wing is provided with sufficient loft to cause an easy elevation of the kite.

The cruciform rudder is next formed by first mounting the innermost of the transverse sticks 30 between the body sticks; slipping the tubular margins 34 of the sheet 33 over the outer portions of the body sticks, and then attaching the outermost of the transverse sticks 30. Previous or subsequent to this operation, the upright sticks 35 may be inserted 70 in the apertures in the transverse sticks 30, and then it is a simple expedient to pass the tubular margins 37 of the sheets 36 over the upright sticks 35 to complete the assembly of the kite.

From the foregoing, it will be apparent that I have provided a knockdown kite which is extremely simple to dismantle and assemble with a minimum possibility of injury to any portion of the kite, which is composed of standardized parts, which may be placed in a compact container, and which is extremely economical to manufacture. Moreover, the kite when assembled and flying is possessed of great stability due to the balance and ratio of the flying or wind surfaces thereof, and due to the cruciform tail and dihedral wing. In addition, the kite is of educational value to a child, in that it may be assembled complete in every detail by the child.

I am aware that numerous details of construction may be varied through a wide range without departing from the principles of this invention, and I, therefore, do not purpose limiting the patent granted hereon otherwise than necessitated by the prior art.

I claim as my invention:

1. As an article of manufacture, a knockdown kite including a wing, and a body portion comprising a plurality of resilient sticks 105 attachable adjacent the forward parts thereof to said wing, means disposed between said sticks to maintain the rear parts thereof spaced apart farther than said forward parts, and means associated with said first said means to provide wind surfaces.

2. As an article of manufacture, a kite including a wing, a pair of spaced sticks extending rearwardly from said wing, means disposed between said sticks adjacent the rear portions thereof to increase the spacing therebetween and a flexible sheet connected to said sticks adjacent said means.

3. As an article of manufacture, a kite including a wing, a pair of spaced body sticks extending rearwardly from said wing, a pair of shorter sticks disposed transversely between said body sticks to increase the spacing therebetween adjacent the rear portions thereof, and a sheet of flexible material connected transversely to said body sticks adjacent the rear portions thereof.

4. As an article of manufacture, a kite including a wing, a pair of spaced body sticks extending rearwardly from said wing, a pair

- of shorter sticks disposed transversely between said body sticks to increase the spacing therebetween adjacent the rear portions thereof, and a sheet of flexible material connected transversely to said body sticks adjacent the rear portions thereof, said shorter sticks being retained in position by the resiliency of said body sticks.
5. As an article of manufacture, a kite including a wing, a pair of spaced sticks extending rearwardly, from said wing, a pair of shorter sticks disposed transversely between said spaced sticks to increase the spacing therebetween adjacent the rear portions thereof, a sheet of flexible material connected to said spaced sticks between said shorter sticks, a stick connected transversely to each of said shorter sticks, a flexible sheet connected to said lastly mentioned sticks above said firstly mentioned sheet, and a flexible sheet connected to said lastly mentioned sticks below said firstly mentioned sheet.
10. As an article of manufacture, a kite including a wing, a pair of spaced sticks extending rearwardly from said wing, a pair of transverse sticks held between said spaced sticks by the resiliency thereof to increase the spacing therebetween, a sheet of flexible material connected to said spaced sticks between said transverse sticks, a pair of upright sticks attached to said transverse sticks, and a sheet of flexible material connected to said last mentioned sticks to provide a rudder and prevent separation of said transverse sticks.
15. 7. As an article of manufacture, a kite including a wing, body sticks extending rearwardly therefrom, and a cruciform rudder formed of a plurality of sticks, and flexible sheets each connectible to a pair of said sticks, said rudder being retained in position by said sheets and the resiliency of said body sticks.
20. 8. The combination in a kite of a single horizontal wing having straight tension members joining the ends thereof to bow said wing and form a dihedral, a body section comprising a pair of spaced resilient sticks attachable adjacent the forward part thereof to said wing, and a cruciform rudder formed of a plurality of sticks and flexible sheets each connectible to a pair of said sticks, certain parts of said rudder being disposed between the body sticks and held in position by the resiliency of said body sticks.
25. 9. In a kite, a wing section comprising a pair of resilient wing sticks having pointed ends, a flexible sheet connecting said wing sticks, a pair of rigid end members apertured at each end thereof to receive said pointed ends and hold said wing sticks in spaced relationship and having inwardly turned apertured tips at each end, and a pair of tension members shorter than said wing sticks and adapted to join said tips and bow said resilient sticks to provide said wing with a dihedral.

10. As an article of manufacture, a kite including a wing, body sticks extending rearwardly therefrom, and a cruciform rudder comprising a pair of transverse sticks resiliently held by said body sticks, a flexible sheet between said transverse sticks, a pair of vertical sticks bisecting said transverse sticks and passing therethrough, and flexible sheets connectible to said vertical sticks above and below said transverse sticks.

11. As an article of manufacture, a kite comprising a wing, a pair of spaced resilient body sticks connected to said wing, and a rudder for said kite disposed between and held in position by the resiliency of said body sticks.

In testimony whereof I have hereunto subscribed my name at Council Bluffs, Pottawattamie County, Iowa.

TOM W. BESLEY.
